UNITED STATES PATENT OFFICE.

PAUL H. QUACKENBUSH, OF HERKIMER, NEW YORK, ASSIGNOR OF ONE-HALF TO
HENRY M. QUACKENBUSH, OF HERKIMER, NEW YORK.

COASTER.

964,809.

Specification of Letters Patent. Patented July 19, 1910.

Application filed February 9, 1910. Serial No. 542,845.

To all whom it may concern:

Be it known that I, PAUL H. QUACKENBUSH, a citizen of the United States, residing at Herkimer, in the county of Herkimer and State of New York, have invented certain new and useful Improvements in Coasters, of which the following is a specification.

This invention relates to coasters or sleds, and provides a combined sled and toboggan designed to unite the advantages of each in a single structure, capable of use for either kind of coasting without change or alteration of any sort.

The essential idea of the invention is the forming of a toboggan and sled in a single structure, such that the sled runners form side pieces or hand holds upon the toboggan, and the toboggan top forms the top of the sled when the structure is used as a toboggan or as a sled respectively.

I illustrate the preferred embodiment of the invention in the accompanying drawing, which gives a perspective view of the coaster.

In the drawing, 1 represents the side pieces of the toboggan which, it will be understood, also form the sled runners. These are parallel with each other and are curved as at 2 and 3 to form the rounded ends of the sled runners and toboggan, respectively.

The curvature at 3 is not necessarily the same as the curvature at 2, each being adapted to secure the best results for sled or toboggan, as the case may be.

One edge of the side pieces 1 is provided with a metal shoe or runner 4, which is indicated as being a flat shoe, but might be of any of the well known types of sled runner. The side pieces 1 are connected by cross pieces or frames 5 and 6, the cross frames 5 being located at the extreme lower edge of the side pieces 1, as viewed in the drawing, and the cross frames 6 being located at the point of juncture of the curvature of the portions 2 and 3 of the side frames. In this way maximum clearance is given under

the coaster when used as a sled. To these cross frames is attached a series of longitudinal wooden strips 7 of suitable thickness, the strips being laid closely together and sprung to the curvature 3 of the side frames 1. These strips form the bottom of the toboggan, curving upward at the forward end in the well known manner.

When used with the runners upon the snow, the coaster serves as a sled, the strips 7 forming the top of the sled. By inverting the coaster it appears as shown in the drawing, and may be used as a toboggan, the strips then being the toboggan bottom in contact with the snow, and the side frames 60 serving to close in the sides of the toboggan and to give a hand hold to the occupants.

It is of course apparent that the structure may be varied between quite wide limits without departing from the spirit of the invention, and that the proportions, design of the curves and the like may be changed to suit individual preferences and conditions.

Having thus described my invention, what I claim is:—

1. In combination with a toboggan, side pieces attached to the sides of the toboggan and adapted to serve as runners when the toboggan is inverted.

2. In a coaster, the combination of sled 75 runners and a curved top attached thereto and adapted to serve as a toboggan when the coaster is inverted.

3. In a coaster, the combination of a frame, a toboggan bottom; and sled runners, 80 the toboggan bottom and the runners being located on opposite sides of the frame.

In testimony whereof I have signed my name to this specification in the presence of two subscribing witnesses.

PAUL H. QUACKENBUSH.
